CLAIM

The ornamental design for a wall-mounted cleat for picture frame, as shown and described.

DESCRIPTION

FIG. 1 is a front perspective view of a wall-mounted cleat for picture frame showing my new design;

FIG. 2 is a left side view thereof;

FIG. 3 is a right side view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a rear perspective view thereof.

The wall-mounted cleat for picture frame is shown with a symbolic break in its length. The appearance of any portion of the article between the break lines forms no part of the claimed design.
